UNITED STATES PATENT OFFICE.

ELIHU THOMSON, OF SWAMPSCOTT, MASSACHUSETTS, ASSIGNOR TO GENERAL ELECTRIC COMPANY, A CORPORATION OF NEW YORK.

HIGH-POTENTIAL INSULATOR.

1,255,667.

Specification of Letters Patent. Patented Feb. 5, 1918.

Application filed January 9, 1913. Serial No. 740,979.

To all whom it may concern:

Be it known that I, ELIHU THOMSON, a citizen of the United States, residing at Swampscott, county of Essex, State of Massachusetts, have invented certain new and useful Improvements in High-Potential Insulators, of which the following is a specification.

My invention relates to high potential insulators which may be used for high potential terminals and the like and has for its general object an improvement in such devices.

When electric conductors carrying a high potential are brought out from the casings used to contain electrical apparatus, such as transformers, switches and the like, or, when such conductors, which may form a portion of transmission lines, are brought into buildings, it has been found that there is a very great tendency for the insulation surrounding the conductor to break down at or near the point where the conductor passes through the wall of such casing or building.

The object of my invention is to provide an insulator which will resist the tendency to break down when subjected to very high differences of potential, and I accomplish this object by utilizing the principle of the non-conducting and insulating character of a very high vacuum as a means for preventing such breakdown.

If a vacuum vessel be sufficiently exhausted or if the vacuum within it be made substantially perfect, it becomes impossible to cause a static discharge to pass through it upon the application of potentials of values with which we are familiar.

It is well known that a vessel containing air will have through it a certain resistance to a static discharge, or the passage of an electric current. If such vessel be evacuated, as the vacuum is raised or the air pressure lowered, the resistance of the air chamber in the vessel will decrease until it will reach a minimum. After this minimum is reached and as the vacuum is further increased or the air pressure further diminished, the resistance of the chamber will increase, its resistance rising rapidly until it attains a high value. I employ this principle in the operation of my invention.

I am aware of the fact that it has been proposed to employ the increased resistance of a vacuum as a means for insulating con-

ductors; but the constructions proposed for this purpose have involved joints, gaskets, packings, and the like such as to render it impossible to obtain a vacuum of such a high degree or an air pressure so low that the resistance of this vacuum is greater than would be the resistance of the air if no vacuum were used, or to maintain a high degree of vacuum for a substantially indefinite period, so that the results could only be negative. As far as I am aware, therefore, insulators having vacua sufficiently high to have insulating properties or reduced conductivity as compared with the atmospheric air have not been used for practical purposes.

I accomplish the object of my invention then by surrounding the conductor by a member or a plurality of members preferably formed of glass or quartz or some vitreous material having continuous walls with vacuum chambers formed therein. Such chambers may then be evacuated in any well known manner and sealed, and with this construction a high vacuum may be obtained, and, if the substances forming this insulating member be properly chosen, such a vacuum may be maintained permanently.

For a further understanding of my invention, reference may be had to the accompanying drawing, in which Figure 1 shows in section a terminal embodying my invention, with a portion of the casing of an electrical apparatus to which such terminal may be connected; Fig. 2 shows a modification of my invention, and Figs. 3 and 4 show further modifications.

Referring first to Fig. 1, 1 is a conductor which may have a high voltage impressed upon it and be connected to a source of supply and to translating devices which have not been shown.

Surrounding the conductor is an insulator 2 having walls 3 with a vacuum chamber 4 formed therein. This insulating member, as shown, is jointless and may consist of a lengthened annulus or tubular member lengthened in the direction of the conductor, and preferably made of glass or quartz or some other vitreous material of a kind which can be worked at a high temperature and which can be exhausted and sealed as perfectly as may be desired.

This annulus or tubular member may be

constructed by putting two tubes, one inside of the other, with a space between, and sealing the ends together. Before completely closing or sealing in the vacuum chamber, 5 it is exhausted to as perfect a vacuum as possible and at such a temperature that the occluded gases from the walls are driven off. This temperature will be almost that of fusion. After such evacuation, the chamber 10 may be sealed in the usual manner. While I have described a preferred construction for this insulating member, I do not limit myself to this construction, but any suitable construction for obtaining the 15 desired result may be used.

Surrounding this insulating member 2 is an insulating member 5, which may be formed of porcelain or some other molded material and which may have formed upon 20 it flanges 6 for the purpose of increasing the leakage space over the exterior of the complete insulator in the well understood manner.

In conjunction with member 5, I have 25 shown an insulating member 7, members 5 and 7 being fastened to the casing 8 of the transformer or the like by means of bolts 9.

As shown in the figure, the casing contains oil 10 and the bottom of the terminal 30 is brought below the surface of the oil in the usual manner. It will be obvious, however, that while I have illustrated my invention as applied to a high potential terminal for transformers or switches and the 35 like, which are placed in an oil-filled casing, that with suitable modifications which will be readily understood by those skilled in the art, my invention may be applied to insulating the high voltage conductors forming 40 transmission lines and the like.

Immediately surrounding a conductor 1 is shown an insulating sleeve 11, and the conductor is shown as rigidly fastened to the insulating members 5 and 7 by means 45 of nuts 12.

Surrounding member 2 is shown a plastic material 13, such as an insulating oil, resin or a mixture of the same, and the like.

It will be obvious from an inspection of 50 the figure that in case a puncture or a breakdown of the insulation should take place, it has to pass over the whole length of the terminal or break through the insulating member containing the vacuum chamber, 55 and it is impossible for this to happen because the high vacuum which exists in the chamber is practically a perfect insulator and will stand a very high voltage without allowing a current to flow through it. As 60 I have explained above, it is necessary that this chamber shall be evacuated to such a high degree that the resistance across the walls of the chamber is greater than that which would exist if the chamber were 65 filled with air, and I preferably exhaust

this chamber to such a high vacuum that an ionized gas discharge cannot take place across it, or a vacuum higher than that of a Crookes tube.

Referring now to Fig. 2, I have shown a 70 modification of my invention, consisting in surrounding the conductor 1 with a plurality of insulating members 2' having vacuum chambers 3' formed therein. These insulating members may be arranged as shown 75 in a number of rows, and preferably I so dispose the rows that the insulating members will break joints with each other, as may be seen from an inspection of the figure.

Fig. 3 shows a further modification of 80 my invention, the insulating members 2' with vacuum chambers 3' being necked down so that one member will fit or nest within the other in the manner shown, and there will thus be a double vacuum layer at cer- 85 tain points.

In Fig. 4, I have shown a still further modification of my invention consisting in employing a member 15, in which is formed a space 14, through which the conductor 90 may be run, and having a plurality of concentric vacuum chambers 16. Flanges 17 may, if desired, be formed on the exterior of the insulating member for supporting the same in the usual manner.

While these vacuum chambers may be made of any length, I prefer to make them as shown, with the ones nearest the conductor the longest, the length of the chambers decreasing as their distance from the 100 conductor increases. By such a construction, where the voltage stress is the greatest between the conductor and the casing or wall through which it passes, the number of layers of insulating vacuum are the most 105 numerous. This construction also has the advantage that if one vacuum layer is not quite so good as another in insulation, that is, is not so well exhausted or free from the remaining gases, the several vacuum chambers 110 make up for each others deficiencies and the insulating value is the sum of the whole of them.

While I have described the preferred embodiments of my invention, I do not limit 115 myself to these embodiments but seek in the appended claims to cover all embodiments which are within the scope of my invention and do not depart from its spirit.

What I claim as new and desire to secure by Letters Patent of the United States, is,—

1. An insulator comprising an integrally and hermetically closed vacuum chamber having continuous, jointless walls of vitreous material, capable of maintaining a vacuum for a substantially indefinite period, the chamber being evacuated to such a degree that an ionization discharge cannot take place across the same.

2. An insulator comprising a vitreous annular member having walls with an integrally and hermetically closed vacuum chamber formed therein, capable of maintaining a vacuum for a substantially indefinite period, the chamber being evacuated to such a degree that an ionization discharge cannot take place.

3. In combination, a conductor and an insulation for the same comprising a plurality of integrally and hermetically closed vacuum chambers surrounding the same capable of maintaining a vacuum for a substantially indefinite period, the chambers being evacuated to such a degree that an ionization discharge cannot take place across the same.

4. A high potential terminal comprising a conductor, an insulating member surrounding the same comprising a member having walls with an integrally and hermetically closed vacuum chamber formed therein, the chamber being evacuated to such a degree that a cathode discharge cannot take place across the same, and a second insulating member surrounding said single member.

5. A high potential terminal comprising a conductor, an insulating member surrounding the same comprising a vitreous tubular member having walls with an integrally and hermetically closed vacuum chamber formed therein, capable of maintaining a vacuum for a substantially indefinite period, the chamber being evacuated to such a degree that a cathode discharge cannot take place across the same, and a second insulating member surrounding said single member.

6. A high potential terminal comprising a conductor, an insulating member surrounding the same comprising a vitreous tubular member having walls with an integrally and hermetically closed vacuum chamber formed therein, the chamber being evacuated

ated to such a degree that a cathode discharge cannot take place across the same, a second insulating member surrounding said single member, and means for increasing the leakage surface of the second member. 50

7. A high potential insulating member comprising a plurality of integrally and hermetically closed vacuum chambers, capable of maintaining a vacuum for a substantially indefinite period, the vacuum chambers being evacuated to such a degree that an ionization discharge cannot take place across the same. 65

8. A high potential terminal comprising a conductor, an insulating member surrounding the same comprising a member having walls with an integrally and hermetically closed vacuum chamber formed therein, capable of maintaining a high degree of vacuum for a substantially indefinite period, the chamber being evacuated to such a degree that an ionization discharge cannot take place across the same, a second insulating member surrounding said single member, and a plastic material between said 70 members.

9. A high potential terminal comprising a conductor, an insulating member surrounding the same comprising a vitreous tubular member having walls with an integrally and hermetically closed vacuum chamber formed therein, capable of maintaining a high degree of vacuum for a substantially indefinite period, the chamber being evacuated to such a degree that an ionization discharge cannot take place across the same, a second insulating member surrounding said single member, and a plastic material between said members. 75 80

In witness whereof, I have hereunto set my hand this sixth day of January, 1913.

E.I.IHU THOMSON.
